CONSTRUCTION FOR SEA-SHORE PROTECTION AGAINST EROSION

André Rivière, Bourg-la-Reine, France

Application July 5, 1955, Serial No. 520,004

Claims priority, application France July 6, 1954

13 Claims. (Cl. 61—3)

This invention relates to jetties and more particularly to permeable jetties.

The customary devices or structures heretofore used for protecting seashores against erosion have, in many cases, proved unsatisfactory. In fact, such devices favor an accumulation of sediment on their leeside and at the same time they reject the littoral current seaward promoting thus a dispersion of the sediment in a way similar to that sort of dispersion which sometimes occurs through the action of currents which in oceanography are termed "rip-currents."

On the leeside of the known structures it is frequently noticed that a turbulent backwash or whirl current occurs which provokes erosion sometimes down to the lowest point of the protective structure staked on the coast with the result that the sea may pass around such structure. Even more frequently it is noticed that erosion is greater at such parts of the shore construction or structure where the wind blows leeside.

Such drawbacks are serious enough to justify the conclusion that the customary shoreline protective structures are sometimes more harmful than useful.

Various improvements have already been made to the establishment of protective structures: such are, for instance, constructions of the surbased type—so-called "Dutch" type—or constructions or structures of the Faraman type. Such device which have proved in certain cases to give excellent results may, however, lead in other cases to drawbacks of the above-described kind. Moreover, constructions of the Dutch or Faraman type are always rather expensive.

A principal object of the present invention is a new type of protective structure to protect a shore having as its main characteristic the fact that it is built in two portions leaving between them a permeable zone which is preferably a gap or cut extending over the whole of the height of the construction or over part of its height, e.g. a so-called "continental" or landward portion well secured into the shore and a seaward portion.

Other features and advantages of the shore protective structure in accordance with the present invention will be better understood as described in the following specification and appended claims, in conjunction with the following drawings in which

Fig. 1 is a plan view of a known type of shore protective structure, and is illustrative of the action of such structures,

Fig. 2 is a diagrammatic plan view of a protective structure according to the invention illustrating the manner in which the structure functions to cause deposition of sediment on both sides of an inner portion of the structure causing the shoreline or beach to "grow" rather than be eroded,

Fig. 3 is a side elevation view of a protective structure of the type shown in Fig. 2,

Fig. 4 is a plan view of the protective structure shown in Fig. 3,

Figs. 5 through 12 are plan views of shoreline protec-

2

tive structures according to the invention, and illustrate various configurations of the spaced portions jointly forming the structure,

Fig. 13 is a side elevation view of a structure according to the invention and illustrates that the structure portions may be partially submerged and need not extend above the surface of the water through their respective lengths.

As indicated heretofore, known protective shore structures of the solid kind have a serious deficiency in that the leeside of the structure is subjected to turbulent backwash as a result of which the leeward shoreline adjacent the structure is eroded. The reason for such defective operation is illustrated diagrammatically in Fig. 1 in which a protective structure 1 of the solid kind is disposed for protecting a shore or beach 2. The prevailing incoming swells arrive from the direction denoted by the arrow H. The direction of the littoral current is denoted by C₁ and is dispersed to the open sea as dispersive currents C₂. The leeside of the structure 1 is subjected to turbulent backwash C₃ causing an erosion of the shoreline in a lee-side area 4.

According to the drawings a shore protective structure in accordance with the invention is constructed, Fig. 2, as a single continuous inner portion 5A starting at the shore and extending toward the open sea so as to form an angle with the shoreline. This inner portion is impermeable to sediment and has a substantially greater longitudinal dimension than its transverse dimension. An outer impermeable portion 5B is disposed spaced seawards from the inner portion forming a zone or gap 6 between the two portions which is permeable to sediment. The outer portion preferably has a greater longitudinal dimension than its transverse dimension.

Here again, the direction from which the sea swell is coming is shown by arrow H. The path taken by the shore-current is shown by arrow C₁. The direction shown by arrows C₂ is that taken by the sea swell current arising from the outer portion 5B of the construction. Arrow C₃ shows the direction taken by the current formed by the wind due to a combination between currents C₁ and C₂. In the hatched areas 7, 8 a build-up of the shoreline has taken place.

The distance between the two portions of the construction has to be determined in accordance with the characteristics of the sea swell and the grade at which the particles are carried away along the littoral.

Under such conditions, repeated observation has shown that, even in case the displacement of sediment particles remains low or in case the natural losses by dispersion are very high, build-up increases on either side of the construction. Such sort of increase or deposition on both sides of the construction results in protection of the coast within the active area of the construction or structure.

The dynamics according to which the construction is operating may be explained as follows in accordance with what has been proven from tests made on miniature models:

The so-called "continental" portion 5A of the construction acts, with respect to the sediments carried away by the shore stream, in a way similar to that which occurs in a customary construction, the shore receiving in consequence a feed lee-ward at 7;

The swell current which tends to arrive along the off-portion or seaward portion 5B is not nullified—as it is in the case of the customary construction—by the shore-stream which is swerved seaward, but can develop freely so as to join the latter at gap 6.

Both currents are carrying sediment which they transfer onto the zone lying see-side of the construction so as to secure a build-up at 8.

It should be stated that:

The amount of material required for a structure according to the present invention is smaller than in the customary forms of construction;

The construction according to the present invention does not give rise to any dispersion of the sediments in an off-shore direction;

The construction according to the present invention is based on a principle which is entirely different from the basic idea underlying any construction of frontal, oval, circular or transversally extending type, such as established namely by Faraman.

Figures 3 and 4 which represent respectively a side elevation view and a plan view section, show diagrammatically, by way of example, a construction in accordance with the present invention, all reference figures being identical with those of Figure 2.

The construction is made up in two straight-line portions of which 5A is the inner or continental portion and 5B the outer or seaward portion.

The length of gap 6 is of the order of 25% of the total length of the construction.

In the embodiment in Figure 5 the outer portion D of the construction or structure is offset with respect to the "continental" portion C, remaining parallel to the latter, so that the centerline of both portions are parallel but offset. It being understood that the offset can be made either on one side depending upon the prevailing sea conditions or on the opposite side.

In the embodiment in Figure 6, the outer or seaward portion D has been positioned in a different way than that of the "continental" portion and its end nearest to the shore has been offset with respect to the continental portion, either to the left or to the right, at whatever desired orientation. The two portions have their centerlines so oriented that projections thereof would intersect forming a complementary pair of angles which are an obtuse angle and an acute angle.

In the embodiment in Figure 7, the seaward portion D is situated at right angles with the continental portion C and may occupy with respect to the latter whatsoever desired position.

In Figure 8 the seaward end of the continental portion C ends with a frontal element or bulbous end F. In a same manner the seaward portion D ends at its seaward end with a frontal element or bulbous end F1. Said frontal element could, moreover, be located at the other end of the seaward or outer portion or the latter might be provided at both ends with bulbous ends. In any of above described embodiments, a frontal element of any type whatsoever may be provided so that the end so provided has a more transverse dimension than the opposite end.

As can be seen in Figures 9 through 12 the plan projection of the axis of the outer portion or of the continental portion, or of both of them, may include one or more curves the shallow part of which can be positioned in a given direction or in the opposite one, the relative positioning of the two portions, the outer and the inner or continental, being situated as desired, as in the cases previously contemplated. The height may vary from one end to the other end of the construction and in some cases it may be contemplated to build the outer portion as well as the continental portion, or both of them, in the form of a submerged construction, in part or in totality. Moreover, it will be noted that in the embodiments shown in Figs. 5 through 12 the outer portion is disposed offset toward the leeward of the seaward end of the inner portion, that is, offset to leeward of the longitudinal centerline of the inner portion.

As will be seen in Figure 13 in which the sea-level is seen at N, the continental as well as the outer portion are both practically submerged.

In certain cases, it may be advantageous to build the outer portion in conformity with or in different positioning

from that used for the continental portion or even to give it a curved projection or again to divide it into multiple outer portions, not shown.

The gap separating the two portions of the construction may, in some cases, be replaced by a set of pile work or obstacles, or by a portion of submerged construction, so as to slow down the movement of the sediment without, however, stopping it.

The above devices which have been described or shown apply, of course, whatever may be the number and the spacing of such constructions or structures and whatever be the form of the edges of the gap or gaps or previous areas.

Whatsoever mode of construction may be resorted to according to personal preference: pile planks, masonry, gabionade, etc., since the profile of the construction does not interfere practically with the mechanism of sediment formation.

Such embodiments which have been described by way of non-limitative examples may be made use of either separately or in combination, though remaining within the objects of the invention.

Specifically the transverse section of the construction may be of any desired shape, particularly rectangular, as in the examples represented on the appended drawings or in any manner, according to the local conditions, the profiles of the two parts of the structure being eventually different from each other.

What I claim is:

1. A structure for protecting seashores comprising, in combination, a single continuous inner portion starting at the shore and extending toward the open sea so as to form an angle with the shoreline, said inner portion being impermeable to sediment and having a substantially greater longitudinal dimension than its transverse dimension and disposed with its longitudinal dimension substantially transverse to the shoreline, a single continuous outer portion disposed spaced seawards from said inner portion in position to form a predetermined zone between the two portions permeable to sediment and through which current flow is directed in a predetermined direction for depositing sediment on the shoreline adjacent opposite sides of said inner portion, and said outer portion being impermeable to sediment and having a substantially greater longitudinal dimension than its transverse dimension.

2. A structure for protecting seashores in accordance with claim 1, in which said inner and outer portions each have a longitudinal centerline, said portions being positioned so that said centerlines are substantially in the same plane.

3. A structure for protecting seashores in accordance with claim 1, in which said inner and outer portions each have a longitudinal centerline, said outer portion being positioned so that its centerline is in a plane substantially parallel to a plane coinciding with the longitudinal centerline of said inner portion.

4. A structure for protecting seashores in accordance with claim 1, in which said inner and outer portions each have a longitudinal centerline, said portions being positioned so that said centerlines coincide with planes intersecting one with the other, and the outer portion being disposed to leeward of a plane coinciding with the centerline of the inner portion.

5. A structure for protecting seashores in accordance with claim 4, in which said intersecting planes form acute and obtuse angles one with the other.

6. A structure for protecting seashores in accordance with claim 4, in which said planes intersect at substantially 90° and the outer portion extends transversely of a plane coinciding with the centerline of the inner portion.

7. A structure for protecting seashores in accordance with claim 1, in which each of said portions has a larger

transverse dimension adjacent a seaward end than the opposite end thereof.

8. A structure for protecting seashores in accordance with claim 1, in which said seaward end of each portion is bulb-shaped.

9. A structure for protecting seashores in accordance with claim 1, in which said inner portion is substantially straight and said outer portion is arcuate, and in which the inner portion has a longitudinal centerline and the outer portion is disposed to leeward of a plane coinciding with said inner portion centerline.

10. A structure for protecting seashores in accordance with claim 1, in which said inner portion has ends offset one with respect to the other, and said outer portion is substantially straight and has a straight part having a 15 longitudinal centerline, and in which the outer portion is disposed to leeward of a plane coinciding with the inner portion centerline.

11. A structure for protecting seashores in accordance with claim 1, in which said inner portion has a part adjacent a seaward end thereof constructed substantially arcuate, said outer portion being arcuate in a reverse 20

direction with respect to the arcuate part of said seaward end of the inner portion said outer portion being disposed to leeward relative to the seaward end of the inner portion.

5 12. A structure for protecting seashores in accordance with claim 1, in which said inner portion has a part thereof adjacent a seaward end constructed substantially arcuate, said outer portion being constructed substantially straight and disposed leeward relative to the seaward end of the inner portion.

13. A structure for protecting seashores in accordance with claim 1, in which said inner and outer portions are partly submerged and partly above the level of the water.
